(57) **CLAIM**

The ornamental design for the concave sign holder, as shown and described.

DESCRIPTION

FIG. 1 is a perspective view of the concave sign holder of the present invention, looking angularly downwardly, towards a front side thereof, the broken lines forming no part of the present invention;

FIG. 2 is a perspective view of the concave sign holder of the present invention looking angularly upwardly, towards the front side thereof, the broken lines forming no part of the present invention;

FIG. 3 is a view of a first end of the concave sign holder of the present invention, the broken lines forming no part of the present invention;

FIG. 4 is a view of a second end of the concave sign holder of the present invention, the broken lines forming no part of the present invention;

FIG. 5 is a front elevational view of the concave sign holder of the present invention; the broken lines forming no part of the present invention;

FIG. 6 is a back elevational view of the concave sign holder of the present invention; the broken lines forming no part of the present invention;

FIG. 7 is a top plan view of the concave sign holder of the present invention; and,

FIG. 8 is a bottom plan view of the concave sign holder of the present invention; the broken lines forming no part of the present invention.
